UNITED STATES PATENT OFFICE.

GLEN D. BRADY, OF DETROIT, MICHIGAN, AND ALVAH C. ROEBUCK, OF CHICAGO, ILLINOIS, ASSIGNORS TO THE ENTERPRISE OPTICAL MANUFACTURING COMPANY, OF CHICAGO, ILLINOIS, A CORPORATION OF ILLINOIS.

CARBON HOLDER.

Application filed April 17, 1922. Serial No. 554,064.

Our invention relates to carbon holders and has for one of its objects the provision of a simple and efficient carbon holder particularly adaptable for projection apparatus, 5 but it may be utilized for holding all kinds of electrical arc carbons.

A further object is the provision of a carbon holder having the adjusting part of the carbon clamp positioned at a distance away 10 from the carbon so as to facilitate the operation and adjustment of the holder.

A still further object is the provision of a carbon holder of the character mentioned, 15 efficient in operation and adapted to give maximum service.

Other objects will appear hereinafter.

An embodiment of our invention is illustrated in the accompanying drawing forming a part of this specification and in which— 20 Fig. 1 is a top view of a carbon clamp and mounting embodying our invention with portions cut way to expose underlying parts;

Fig. 2 is a vertical section taken through the carbon clamp; and

Figs. 3 and 4 are sections taken on lines 3—3 and 4—4, respectively, of Fig. 2.

Referring more particularly to the drawing, a support 5 is indicated for holding the carbon holder. This support may be the 30 supporting arm of an arc lamp of any desired or preferred construction. It will be understood that two of these arms 5 are used in each lamp and also two of the carbon holders will be necessary.

Our improved carbon holder comprises a tubular member 6 mounted on an arm 5 by screws 7, or their equivalent. The member 6 is insulated from the arm 5 and screws 7 by insulation material 8, such as mica, or any 40 other desired substance. This insulation is applied in the usual manner.

The member 6 is preferably hollow and provided with arms 9 at its outer end which reach around a space 10 in which the carbon 45 11 is to be held. These arms 9 are arranged so as to form a substantially C-shaped clamp with the opening directed away from the hollow or tubular opening 12 in the member 6. The opening 10 is preferably large enough 50 to permit the use of the largest size carbon that may be desirable.

Disposed within the tubular opening 12 is a clamp member 13 which is preferably small enough to permit its movement freely in the

opening 12 when the parts are heated in use. 55 One end of the member 13 is V-shaped as at 14 to engage the carbon and clamp it tightly against the arms 9, as clearly indicated in Fig. 2. A screw 15 is threaded in the wall of member 6 and extends into opening 12 with its end disposed within a groove 16 in 60 one side of the member 13 so as to prevent rotation of the latter. The end of member 13 away from the carbon opening is preferably enlarged as at 17 so as to guide the rear end of the member 13 in its opening. 65 The tubular member 6 may have a portion 17' projecting into the opening 12 for engaging the member 13 to support the carbon-engaging end of the latter. The members 17 and 17' provide means for mounting member 13 in member 6 with minimum contacting surfaces. This has the advantage of reducing interference from rust, carbon ash, 70 dirt, expansion from heat, etc., between said members. It will be apparent that members 17 and 17' may be eliminated when so desired and member 13 fitted loosely in member 6. 75

The member 13 has a recess 18 in its rear end in which a screw 19 extends. The screw 19 preferably has an annular groove 20 in which are disposed one or more pins 21. The pins 21 are secured in the member 13 and disposed in the groove 20 so as to hold 80 the member 13 against relative longitudinal movement with respect to screw 19. 85

A plug 22 is held in the opening 12 by screws 23, or their equivalent. These screws are indicated as being attached in a manner 90 so as to hold the block 13 both against rotary and longitudinal movements in the opening 12, as clearly indicated in Figs. 2 and 4.

A conductor connection 24 may be attached 95 to the member 6 by screws 25, or their equivalent. The conductor 24 may be of any approved design and construction.

In use, the screw 19 is adjusted longitudinally until the end 14 clamps the carbon 100 against arms 9. The screw and its connection with member 13 is situated a considerable distance from the carbon so as to prevent these parts becoming set due to overheat and oxidation. The member 13 is small 105 enough, as already pointed out, adjacent the carbon to prevent its expansion through heating from binding it in opening 12 and

therefore prevent its sticking. It will be apparent also that by placing the screw at a distance from the carbon it can be adjusted at any time. The screw 19 preferably engages the bottom of the recess 18 so that no pressure is on the pins 21 during clamping the carbon; said pins simply are used to withdraw the clamp when loosening the carbon.

10 The opening between the free ends of prongs 9 has a two-fold object, one of which is to assist in alining the two carbons with each other, and the other object is that this opening is of especial benefit in the upper 15 carbon holder when the carbon is burnt to a point near the carbon holder, in which case the flame from the arc does not overheat the carbon holder.

We claim:—

20 1. A carbon clamp comprising a member having a carbon-engaging portion provided with an opening for receiving a carbon and having a guideway arranged transversely of said opening; a movable carbon-engaging 25 member adjustably mounted in said guideway and spaced from the walls thereof and having a portion cooperating with the carbon-engaging portion of said member and spacing means to prevent binding between 30 said carbon engaging member and its guideway.

35 2. A carbon clamp comprising a tubular member having a carbon-engaging arm at one end thereof; a clamp member slidably mounted in the tubular member with a carbon-engaging portion at one end; means for spacing said clamp member from the walls of said tubular member, and means for adjusting the clamp member in said tubular 40 member.

45 3. A carbon clamp comprising a tubular member; a clamp member disposed within said tubular member, combined spacing and supporting means providing limited sliding engagement between said tubular member and said clamp member to hold the walls of said members in spaced relation to each other, said clamp member being sufficiently small so as to be easily movable while the 50 parts are in highly heated condition; and a screw mounted in the tubular member and engaging the clamp member for longitudinal adjustment of the latter in said tubular member.

55 4. A carbon clamp comprising a member having a carbon-engaging arm thereon; a

clamp member slidably mounted with relation to the first-mentioned member toward and away from said arm; a removable plug in said first-mentioned member having a 60 threaded opening therein, and an adjusting screw having end thrust bearing in said plug for moving the clamp member toward and away from said arm.

5. A carbon clamp comprising a tubular 65 member having carbon-engaging arms curved toward each other; a clamp member mounted in said tubular member and having a recess in one end; and a screw adjustably mounted in the tubular member with 70 one end engaging the recess in said clamp member.

6. A carbon clamp comprising a tubular member having carbon-engaging arms curved toward each other; a clamp member 75 mounted in said tubular member and having a recess in one end; a screw adjustably mounted in the tubular member with one end engaging the recess in said clamp member; and means connected with the screw 80 and clamp member for holding such members against relative longitudinal movements.

7. A carbon clamp comprising a tubular member having a C-shaped opening at one 85 end; a clamp member mounted in the tubular member and movable toward and away from the open side of said C-shaped opening; a screw adjustably mounted in the tubular member; and means holding the screw 90 against relative longitudinal movements with respect to the clamp member.

8. A clamp member comprising a tubular member having carbon-engaging arms extending toward each other; a carbon clamp 95 having an angular end adjacent said carbon-engaging arms and a recess in its other end; a block held in said tubular member; a screw threaded in said block and extending into said recess; and pins mounted in said clamp member and engaging said screw for holding the clamp member against relative longitudinal movements with respect to the screw.

In testimony whereof I have signed my 105 name to this specification on this 12th day of April A. D. 1922.

ALVAH C. ROEBUCK.

In testimony whereof I have signed my 110 name to this specification on this 11 day of April, A. D. 1922.

GLEN D. BRADY.
